UNITED STATES PATENT OFFICE.

ERNEST L. HOSPES AND LOUIS NAPOLÉON BERGERON, OF STILLWATER,
MINNESOTA.

CONVEYER FOR SAW-MILL REFUSE.

SPECIFICATION forming part of Letters Patent No. 367,102, dated July 26, 1887.

Application filed January 31, 1887. Serial No. 226,073. (No model.)

To all whom it may concern:

Be it known that we, ERNEST LOUIS HOSPES and LOUIS NAPOLÉON BERGERON, citizens of the United States, residing at Stillwater, in the county of Washington and State of Minnesota, have invented an Improvement in Conveyers for Saw-Mill Refuse and other Substances; and we do hereby declare that the following is a full and exact description of the same, reference being had to the accompanying drawings, making part of this specification.

In the drawings, Figure 1 represents a top view of a portion of the trough, endless chain, and one of the sweeps or scrapers of a saw-mill-refuse conveyer provided with our improvement; Fig. 2, a longitudinal vertical section of the same parts in a plane indicated by the line *xx*, Fig. 1; Fig. 3, a transverse vertical section thereof in a plane indicated by the line *yy*, Fig. 1; Fig. 4, a view in perspective of the part in which our invention consists.

Like letters designate corresponding parts in all of the figures.

Our improvement is especially applied to conveyers for sawdust and other refuse in saw-mills; but it is applicable to conveyers of other substances or materials, in which an endless chain is used as the means for operating the conveyer.

Our improvement consists in a double shoe or clasp for uniting the cross sweeps or scrapers with the endless chain, whereby the said sweeps or scrapers are held rigidly at right angles to the line of motion, and this with a single endless chain for drawing the sweeps or scrapers.

In the drawings, A represents a portion of a trough in which the refuse or other material is conveyed; B, one of the sweeps or scrapers for conveying the same along in the trough, and C an endless chain, to which the sweeps or scrapers are attached, for communicating motion thereto.

In the bottom of the trough A is a sunken channel, *a* in which the endless chain travels below the sweeps or scrapers, which slide laterally over the bottom of the trough. The endless chain is ordinarily made up of alternate solid horizontal links *b b* and vertical strap-links *c c*. It is to the solid links, as *bb*, that the sweeps or scrapers are attached, as represented in the drawings.

We employ a clasp, D, for each sweep or scraper, by which the same is held firmly at right angles to the trough or line of motion. This clasp is a double one, as shown in Fig. 4, there being two pairs of clasping-flanges, *d d* and *ff*—one pair, as *dd*, to clasp against the sides of the sweep or scraper B, and the other pair, as *ff*, to clasp against the sides of the chain-link *b*—and the two pairs of flanges are at right angles to each other. A single bolt, *g*, passes down through the middle of the sweep or scraper, the clasp, and the link, and the said parts are held together by this bolt and a nut, *h*, screwed upon the bolt. The clasp may be made of malleable iron or common cast-iron.

The construction resulting from this improvement is exceedingly simple and cheap, as well as strong, durable, and effective.

We claim as our invention—

In a conveyer, the combination of the clasp D, having two pairs of clasping-flanges, with a sweep or scraper, B, and chain-link *b*, substantially as and for the purpose herein specified.

In testimony whereof we have hereunto set our hands in the presence of two subscribing witnesses.

ERNEST L. HOSPES,
LOUIS NAPOLÉON BERGERON.
